UNITED STATES PATENT OFFICE.

DANIEL SPOONER, OF BLUE MOUND, ILLINOIS.

SMOOTH-ROPE AND KNOTTED-WIRE CHECK-ROWER.

SPECIFICATION forming part of Letters Patent No. 278,622, dated May 29, 1883.

Application filed February 10, 1883. (No model.)

To all whom it may concern:

Be it known that I, DANIEL SPOONER, residing in the town of Blue Mound, in the county of Macon and State of Illinois, have invented a new and useful Improvement in Smooth-Rope and Knotted-Wire Check-Rowers, of which the following is a specification, reference being had to the accompanying drawings and letters of reference marked thereon, in which—

Figure 1 is a plan view of my smooth-rope check-rower. Fig. 2 is a side elevation of the same, and Figs. 3 and 4 are detail views.

My invention relates to improvements in smooth-rope and knotted-wire check-rowers; and it consists in the peculiar construction and arrangement of the parts, as hereinafter more fully set forth, and pointed out in the claims.

In the accompanying drawings, G G represent two semicircular cam-plates, the planes of which are inclined to each other and joined together along their common diameter, provided with a longitudinal opening for the reception of the shaft C, keyed thereto.

F represents a post adjustably secured to the lower face of the measuring-wheel A, over the semicircular cam-plates G, by means of nuts, and provided at its lower end with a friction-wheel, b, adapted, in the revolution of the measuring-wheel, to be brought to bear first on one and then on the other of the semicircular cam-plates G, and thus impart a rocking motion to the shaft C. The semicircular cam-plates G, secured together with their planes inclined to each other, thus form a cradle, D, rocked back and forth by means of the post F and its friction-wheel b at each revolution of the measuring-wheel A. The post F is made adjustable in its length by nuts, to compensate for any wear on the cradle. The friction-wheel b travels over each semicircular cam-plate G of the cradle D alternately in such a manner as to hold it down on the face of the bar M, as shown in Fig. 3, and thereby forming a lock, and obviating the difficulty heretofore experienced by the rebound of the slide-bar of the planter between strokes in passing over rough ground.

The connection between the rock-shaft C and the slide-bar of the planter is made by the

slotted arm I, provided with a wrist-pin. Two forks or clutches set into the periphery of the measuring-wheel, and flush with the outer surface of the same, and at exactly opposite points of diameter, and the side pulley, may be so arranged as to lift each knot out of the fork as soon as another knot is engaged, thereby preventing any slipping of the wire on the wheel. The outside wheel is grooved, and is designed merely to act as a guard to prevent the wire from slipping off in turning around, so that by passing a knotted wire over a large wheel power is gained in working the seed-slide, and the jerking common to a knotted rope and wire check-rower is obviated.

It is designed in this invention to provide for drilling seed as well as planting. To accomplish this result the cradle D is detached, and a system of cams, G, adjusted in such a manner as to receive motion from corresponding posts, F, carrying friction-wheels attached to the alternate arms of the measuring-wheels A at varying distances from its center, so as not to conflict with each other in reversing the cams and to impart a reciprocating movement to the slide-bar of the drill.

B represents an iron wheel provided with a grooved tire, (not shown in the drawings,) in which is inserted a rubber roll, L, as used on bicycles, and is designed to engage in the groove in the periphery of the measuring-wheel A, in such a manner as to compress the rope P and prevent its slipping on the wheel A. The wheel B is attached to the slide J, and is kept in contact with the measuring-wheel A by means of the spring K.

H represents an angular bar extending across and under the wooden bar N, at right angles thereto, and supporting said bar and the parts resting thereon, one of the upright arms of the angular bar H provided with a horizontal arm, O, having a recess in which the slide J, carrying the wheel B, operates, the latter being always pressed against the circumference of the measuring-wheel A by the spring K, to prevent the rope P from slipping.

Having thus fully described my invention, what I claim as new, and desire to secure by Letters Patent, is—

1. The combination, with a measuring-wheel, of a cradle, D, constructed substantially as de-

scribed, and adapted to impart a reciprocating motion to a seed-slide, as set forth.

2. The combination, with the measuring-wheel A, provided with the post F and friction-wheel b, of the cradle D, rock-shaft C, and slotted arm I, provided with a wrist-pin adapted to be attached to a slide-bar, substantially as described, and for the purpose set forth.

3. The combination, with the grooved measuring-wheel A and its rope P, of the angular bar H, having the horizontal recessed arm O, secured to the upper end of one of its uprights, slide J, carrying the wheel B and adapted to move in the recess in the arm O, and spring K,

secured to one end of the slide and to the upright of the bar H, substantially as shown and described.

4. The combination, with the grooved measuring-wheel A, provided with the post F, having friction-wheel b at its lower end, cradle D, and beam N, of the angular bar H, supporting said beam, and shaft C, keyed to the cradle and journaled in the uprights of the angular bar H, substantially as shown and described.

DANIEL SPOONER.
